UNITED STATES PATENT OFFICE.

DAVID FISHER, OF PADEN CITY, WEST VIRGINIA, ASSIGNOR TO PADEN CITY GLASS MANUFACTURING COMPANY, OF PADEN CITY, WEST VIRGINIA, A CORPORATION OF WEST VIRGINIA.

DESIGN FOR A GLASS TUMBLER.

Application filed April 5, 1928. Serial No. 26,137. Term of patent 3½ years.

To all whom it may concern:

Be it known that I, DAVID FISHER, a citizen of the United States, residing at Paden City, in the county of Wetzel and State of West Virginia, have invented a new, original, and ornamental Design for Glass Tumbler, of which the following is a specification, reference being had to the accompanying drawing, forming a part thereof.

I claim:

The ornamental design for a glass tumbler, as shown.

DAVID FISHER.
